UNITED STATES PATENT OFFICE

ALFRED LEO PEEL, OF BIRMINGHAM, ENGLAND

FASTENING FOR ATTACHE CASES, BAGS, TRUNKS, AND THE LIKE

Application filed December 2, 1930, Serial No. 499,449, and in Great Britain December 6, 1929.

The invention relates to fastenings for attaché cases, trunks, gramophone and wireless cases and the like of the kind formed by two principal members, the one comprising a lug rigidly fixed to the lid or body and the other comprising a link and a hand lever, or equivalent part, attached to the body or lid, these two members to co-operate by the link engaging the lug to pull the lid and body closely to each other from the hand lever or like action, and hold them so. There is usually an undercut abutment face on the lug for the link to engage.

In the use of such fastenings the link requires to be hand placed over or clear of, the lug while the hand lever or equivalent part is inoperative.

In this kind of fastening the invention provides an arrangement whereby the movements of the link are only controlled by the hand operation of the lever or equivalent part, that is to say, in unfastening, the movement of the lever in one direction first takes the link out of fastening engagement with the lug and afterwards swings it clear of the lug so that the case or trunk may open, and similarly the operation of the lever in the other direction first swings the link over the lug and then pulls the link down into fastening engagement with the lug, there being no separate hand operation of the link.

The link is directly or indirectly connected to the manually operated lever, or part, so that movement of the lever or part in one direction operates to automatically move the link out of engagement with the lug and subsequently swing it or move it clear of the lug so that the bag or case can open, whereas movement of said lever or part back again effects converse movements of said link and fastens the lid and body securely together.

The invention also embodies constructional features to carry out the aforesaid action, and these will be hereinafter described in connection with the accompanying drawings.

Figs. 1 and 2 are respectively a plan and a longitudinal section of one form of the invention.

Figs. 3 and 4 are respectively a plan and

a side elevation of another form of the invention.

Figs. 5 and 6 are respectively a plan and a side section of a third form of the invention.

Figs. 7, 8 and 9 are respectively a plan, side section, and detail of a fourth form of the invention.

With reference to Figs. 1 and 2 the body of the case is represented at *a* and the lid at *c*. The lug *d* is fixed by its attachment plate *d2* 60 to the lid and is arranged with a shoulder *d3* behind which the link, hereinafter described, engages as the equivalent to undercutting of the lug. A hand lever *e* is fulcrumed at *e2* to its attachment plate *f*, whereby the fastenings part is attached to the body *a*, and is hand operated from its end *e3*. To this lever at *g* is fulcrumed the one end of a member *h* having side bars *h2*, *h3* which at their ends *i*, *i* are oppositely pivoted to the inner end of 65 the link *j* which swings about the pivotings *i*, *i*, and near this end is formed with abutments *j2*, *j3*, to co-operate with a fixed bar *l* forming part of the enclosing casing, *x*, secured to the attachment plate *f* to enclose the 70 member *h* and the inner end of the link *j*. The full lines represent the parts described in fastening position pulling the lid *c* closely to the body *a* and holding it so; the link *j* is in engagement with the lug *d*, and the member *h* pulls the link hard against the lug by the closed position of the lever *e*, the pivoting of the member *h* to the lever being at this time inwards of the fulcrumed position 75 *e2* of said lever. The dotted positions of the parts show the lever *e* swung outwardly, the member *h* moved upwardly and the link *j* swung outwardly about the bar *l* but during the action the link *j* is first moved upwardly 80 clear of the shoulder *d3* until the seatings *j2* 85 contact the bar *l*, when the action causes the link *j* to swing outwardly into the dotted position as shown. Conversely the link *j* first swings inwardly over the lug *d* and then pulls downwardly fastening the lid and body 90 of the case to each other.

The construction of Figs. 3 and 4 is substantially similar to the construction of Figs. 1 and 2 and therefore similar letters of reference are used where permissible.

The lug *d* is undercut instead of being formed with the definite shoulder, while the side bars *h*₂, *h*₃, constituting the member are external instead of internal. The opposite 5 slots *j*₃ in the sides of the link *j* engage the bar *l*.

The full lines position show the fastenings in operation, and the dotted lines position the fastenings out of action, the link *j* being first 10 lifted clear of the lug before being swung outwardly.

In the form of the invention Figs. 5 and 6 the link *j* to engage the lug *d* is directly pivoted to the lever *e* at *g* but the middle parts 15 *j*₄, *j*₄ of its side bars are shaped to be guided in holes *c*₂ of an extension *o* of the attachment plate, so that when the lever is hand moved upwardly the link *j* first lifts clear of the shoulder *d*₃ of the lug *d*, and then swings 20 outwardly into the position shown in dotted lines clear of said lug, so that the lid and body can separate.

Where permissible the same letters of reference are used on these figures as in the previous 25 ones.

The form of the invention Figs. 7, 8 and 9 is the same as the form Figs. 1 and 2 except that the hand lever *e* swings at right-angles to the movement of the member *h*, and therefore in these figures the same letters or reference are used where permissible.

The lever *e* in this form of the invention is fulcrumed to the casing at *e*₂ to swing in the plane of the fastenings part, in other words, 35 across the fastenings part, and a bar *r* fulcrumed at *r*₂ to the casing, and connecting at *r*₃ with the lever *e* by pin and slot engagement, is provided with a peg *r*₄ which slidably engages a slotted bar *r*₅ in the member *h* to 40 traverse said member upwardly and downwardly to give the same action for the link *j* as described with reference to Figs. 1 and 2; this form of the invention illustrating simply a different form of hand lever action from the 45 form of Figs. 1 and 2.

Having now described my invention, what I claim and desire to secure by Letters Patent is:—

1. Fastenings for attaché cases, trunks, 50 boxes, gramophone and wireless cases, and the like, comprising in combination, an attachment plate to be secured to one part of the case, a lug to be secured to the other part of the case, a manually operable lever pivoted to the attachment plate, a movable coupling member, one end of which is pivotally connected to said lever, a securing link pivotally connected to the other end of said coupling member and adapted to co-operate with said lug and means for guiding said securing link so as to automatically control the movement thereof from the lever action in coupling and uncoupling the fastenings.

2. Fastenings for attaché cases, trunks, 65 boxes, gramophone and wireless cases, and

the like, comprising in combination an attachment plate to be secured to one part of the case, a lug to be secured to the other part of the case, a manually operable lever pivoted to the attachment plate, a movable coupling member one end of which is pivotally connected to said lever, side bars on the coupling member, a securing link pivotally connected to the other end of said coupling member and adapted to cooperate with said lug, opposite guides on the securing link and projections on the attachment plate to engage said guides so as to automatically control the securing link through manual operation of said lever into and out of engagement with the lug.

3. Fastenings for attaché cases, trunks, boxes, gramophone and wireless cases, and the like, comprising in combination an attachment plate to be secured to one part of the case, a lug to be secured to the other part of the case, a manually operable lever pivoted to the attachment plate, a movable coupling member one end of which is pivotally connected to said lever, side bars on the coupling member, a securing link pivotally connected to the other end of said coupling member and adapted to co-operate with said lug, means for guiding the securing link consisting of a swing bar carried by the attachment plate and located in the path of the link, and abutment seatings on the link to coact with the swing bar so as to automatically control the movement of the connecting link on operating the lever in coupling and uncoupling the fastenings.

4. Fastenings for attaché cases, trunks, boxes, gramophone and wireless cases and the like, comprising in combination an attachment plate to be secured to one part of the case, a lug to be secured to the other part of the case, a manually operable lever fulcrumed to the attachment plate to swing transversely thereon to two positions, a securing link cooperating at its one end with said lug, a swingable member pivoted at its one end to the link and at its other to the lever at a point inwards of the fulcrum of the lever, and means connecting the inner end of the securing link to the attachment plate for automatically controlling the movements of said link from said lever through the intervention of the member to cause said link to positively engage and disengage said lug in coupling and uncoupling the fastenings.

In testimony whereof I have affixed my signature.

ALFRED LEO PEEL.
